FURNACE WALL CONSTRUCTION

Ernest C. Witzke, Bayside, N. Y., assignor, by
mesne assignments, to Combustion Engineering-Superheater, Inc., a corporation of Delaware

Application August 6, 1948, Serial No. 42,944

5 Claims. (Cl. 122—235)

1

This invention relates to furnace walls and more particularly to the construction of water cooled furnace walls adapted for use with steam generators.

My invention is particularly designed to keep all of the steam generating tubes lining the inside surfaces of furnace walls in predetermined alignment and insure a definite direction of expansion of the furnace walls with respect to each other. Furthermore my construction is particularly new and useful in the erection of the furnace wall tubes in that the wall tubes and their stiffening means do not require accurate pre-alignment before assembling them, thereby incurring a substantial saving in the time and cost of erection.

It is accordingly one object of my invention to provide a novel furnace wall construction which will support the furnace wall tubes in spaced alignment while permitting definite directional expansion resulting from changes in temperature.

It is a further object of the invention to provide a novel furnace wall construction which can be erected in a simple expeditious manner and at a relatively low cost.

With these and other objects in view as will be apparent to those skilled in the art, the invention resides in the combination of parts set forth in the specification and covered by the claims appended hereto.

In the drawings:

Fig. 1 is a section through the corner of two adjacent walls of a water cooled furnace taken on the line 1—1 of Fig. 2.

Fig. 2 is a fragmentary section taken on the line 2—2 of Fig. 1.

Fig. 3 is a fragmentary section taken on the line 3—3 of Fig. 1.

Fig. 4 is a diagrammatic plan section of wall support showing anchor point 12 controlling horizontal expansion of buckstay 15.

The embodiment illustrated in Figs. 1 to 3 comprises rows of closely-spaced vertical water tubes 1 and 2 lining the inner walls of the furnace 3. These tubes are connected at their lower and upper ends into headers (not shown) which in turn are connected by tubes (not shown) into the circulation of the boiler in a well known manner. The tubes 1 are arranged in alignment adjacent the walls while the tubes 2 are corner tubes and provide a continuity of water cooled surface within the furnace.

Each of the tubes 1 and 2 is provided with a radially projecting plate 3, 4 or 5 welded thereto at spaced intervals longitudinally of the tube and

on the side of the tube remote from the furnace interior. The plates 3, 4 and 5 are arranged so that one of their edges, in this instance their top edges, lie substantially in a plane normal to the tube. Each plate 3, 4 and 5 is provided with a slot 6 (see Figs. 2-3) adjacent its top edge and the tube for the reception of the flange of an angle 7. The slots 6 of all of the plates 3, 4 and 5 are in substantial alignment. Some of the plates 4 and 5 extend out from the tube a greater distance than the remaining plates 3 for reasons to be described below.

One flange of the angles 7 is supported by or adjacent the top edges of the plates 3, 4 and 5 while the other leg extends into the slot 6 of the plates adjacent the tubes 1 and 2. The angles 7 extend for the full width of the furnace wall and meet the angles 7 of the adjacent wall at the corners of the furnace. The angles 7 provide a means for maintaining all of the tubes in alignment and after erection are welded to the plates 3, 4 and 5 at their contact with the edges of the slot 6. In this manner the angles 7 in conjunction with plates 3, 4 and 5 not only maintain alignment of the tubes in a wall but also serve to maintain a continuity of support for all the aligned tubes and serve as well as to maintain the spacing of the tubes. By so supporting the tubes, the angles 7 supplement the main support of the tubes from the header.

The angles 7 of adjacent walls meet with their top surfaces in the same plane and are provided with a joining plate 8 fastened to their top surface as by welding. An inside clip angle 9 fastens the vertical flanges of these angles together as by means of rivets or bolts. There is provided at the outer edges of said joining plate 8 a corner angle 10 normal to said plate and fastened thereto as by welding. A diagonal rib aids in stiffening the corner structure formed by plate 8 and angle 10. The top of said angle 10 is flush with the bottom of said plate 8. The combination of angles 7 and 10 and the corner plates 8 thus forms a fixed structure surrounding the entire furnace at a predetermined location adjacent the tubes 1 and 2.

As mentioned above certain of the plates 4 and 5 extend from the tubes 1 and 2 for a greater distance than the remaining plates 3. Such plates are shown in Figures 2 and 3; Fig. 3 showing the plate extending from the corner tubes 2. The edges of these longer plates 4 and 5 remote from the tubes 1 and 2 are in substantial alignment and serve to carry the buckstays 11, in this instance in the form of an H beam, surrounding

the furnace. Because perfect alignment of the plates 4 and 5 cannot be expected, I provide clips 12 and 13 whose slots 14 straddle the inner flange 15 of the H beam 11 and when placed in position are fastened to the plates 4 and 5 as by welding. The buckstays 11 are then free to move with respect to the structure supporting tubes by sliding in the slots 14 within the clips 12 and 13. The ends of the buckstays at the corners of a furnace are not fastened together but are free to move, thereby accommodating the difference of expansion between the walls and the buckstays 11.

The top clips 13, adjacent the corners of the furnace, differ from the clips 12 in that their slots 14 are L shaped (see Fig. 3), one edge of the slot being welded to the top of the corner plate 8. The clips 12 just below the clips 13 (again see Fig. 3) have their slots 14 of sufficient width to accommodate the bottom portion of corner angle 10 and the flange 15 of the H beam 11.

To protect the angle 7 from the radiant heat of the furnace which heat may pass between the gaps provided between tubes 1 and tubes 1 and 2, I preferably provide fillers 16, such as rods, which are welded to at least one of the adjacent tubes and may extend only for a small distance beyond the angle 7.

In constructing this wall support, the tubes 1, 2 will first be erected, being supported by the headers (not shown) in a well known manner. These tubes have previously provided in the shop with the plates 3, 4 and 5 which extend outwardly therefrom and are all in substantial alignment transversely of the tubes. Then the angles 7 are placed into the slots 6 of the plates 3, 4 and 5 thereby aligning the tubes, and the ends of the angles of adjacent walls are aligned and fastened to the corner plates 8. The tubes are now properly spaced apart and the angles 7 are then welded to the plates 3, 4 and 5. Fillers 16 may now be tacked welded to the tubes.

Preferably the bottom clips 12 are now aligned with respect to their slots 14 and welded to the plates 3, 4 and 5 so as to provide a support for the flanges 15 of buckstays 11. After the buckstays 11 have been brought into place, the upper clips 12 and 13 are mounted on the flanges 15 and welded to the plates 3, 4 and 5.

In Fig. 2 is shown by way of example, a fragment of one form of wall construction 17 extending between the tubes 1 outwardly to a parallel plane passing through the inner face of the flange 15 of buckstay 11. It comprises an inner heat resisting refractory 18 adjacent the tubes 1, backed by insulation 19 and covered on the outside by a plastic coating 20. A reinforcing 21, such as expanded metal lath, holds the layers of refractory, insulation or plastic in position. Such a construction may extend around all of the walls of the furnace and the angles 7 and plates 3, 4 and 5 are buried therein so that no air or gas leakage passes through the wall.

Any tendency of the tubes to misalign is prevented by the angles 7 and any pressure tending to bow the wall is also resisted by the angles 7 and is further resisted by the reinforcing buckstays 11 since these two are held in spaced apart relation by the plates 4 and 5 and the associated clips 12 and 13. Furthermore the corner construction comprising the plates 8 and the angles 10 welded thereto maintains the furnace shape by their welded union with the adjacent wall angles 7 and their retention of the buckstays 11 by means of the welded on clips 13.

To prevent longitudinal misplacement of buckstay 11 with respect to the remaining wall structure, it may be welded to a certain clip 12', preferably located at the middle of the buckstay or wall (as shown diagrammatically by Fig. 4). Said clip will then serve as an anchor point from which the buckstay may move in either direction.

By my novel combination of parts set forth above, I provide a furnace wall construction which can be erected in a simple expeditious manner and at a relatively low cost. Nor does it require accurate alignment of shop attachments to the tubes as minor errors and inaccuracies can be compensated for on erection without extra field work. There is no field welding to the tubes thus eliminating the possibility of injuring tube by careless welding.

While the preferred embodiment of my invention has been shown and described, it will be understood that changes in construction, combination and arrangement of parts may be made without departing from the spirit and scope of the invention as claimed.

What I claim is:

25. 1. A plastic furnace wall comprising an inner row of water tubes, an outer layer of plastic refractory material, a multiplicity of plates aligned in a row that extends transversely across said water tubes, each of said plates being fastened to its individual tube in a position longitudinal of the axis of said tube, and extending outwardly therefrom, each of said plates being provided with a slot extending substantially parallel to and at a predetermined distance from the tubes, and an angle iron one leg of which extends into said slots for engagement with said plates thereby aligning and spacing all of the tubes in the row, said tubes, plates and angles being embedded in said refractory material layer and forming a unitary wall structure.

2. Plastic furnace walls each comprising an inner row of water tubes, an outer layer of plastic refractory material, a multiplicity of plates aligned in a row that extends transversely across said water tubes, each of said plates being fastened to its individual tube in a position longitudinal of the axis of said tube and extending outwardly therefrom, each of said plates being provided with a slot extending substantially parallel to and at a predetermined distance from the tubes, an angle iron one leg of which extends into said slots for engagement with said plates thereby aligning and spacing all of the tubes in the row, the other legs of said angle irons of adjoining walls being in the same plane, and a corner plate welded to each of said angle irons, said tubes, plates, angle irons and corner plates being embedded in said plastic refractory layer and forming a unitary wall structure.

3. A plastic furnace wall comprising an inner row of water tubes, an outer layer of plastic refractory material, a multiplicity of plates aligned in a row that extends transversely across said water tubes, each of said plates being fastened to its individual tube in a position longitudinal of the axis of said tube, and extending outwardly therefrom, each of said plates being provided with a slot extending substantially parallel to and at a predetermined distance from the tubes, an angle iron one leg of which extends into said slots for engagement with said plates thereby aligning and spacing all of the tubes in the row, said tubes, plates

and angles being embedded in said plastic refractory layer and forming a unitary wall structure, some of said plates extending outwardly for substantially the same distance from certain of said tubes and further than the remaining plates, a buckstay extending transversely of the tubes adjacent the outer edges of said farther extending plates and having a flange substantially parallel to said edges, and clips provided with slots loosely fitting over the edge of said flange and welded to said farther extending plates thereby providing freedom for longitudinal expansion of said inner wall structure with respect to said buckstay.

4. A plastic furnace wall comprising an inner row of water tubes, an outer layer of plastic refractory material, a multiplicity of plates aligned in a row that extends transversely across said water tubes, each of said plates being fastened to its individual tube in a position longitudinal of the axis of said tube and extending outwardly therefrom, each of said plates being provided with a slot extending substantially parallel to and at a predetermined distance from the tubes, an angle iron one leg of which extends into said slots for engagement with said plates thereby aligning and spacing all of the tubes in the row, said tubes, plates and angles being embedded in said plastic refractory layer and forming a unitary wall structure, some of said plates extending outwardly for substantially the same distance from certain of said tubes and further than the remaining plates, a buckstay extending transversely of the tubes adjacent the outer edges of said farther extending plates and having top and bottom flanges substantially parallel to said edges, and top and bottom clips provided with slots loosely fitting over the edges of said flanges and welded to said farther extending plates thereby supporting said buckstay from said wall structure and providing freedom for longitudinal expansion of said inner wall structure with respect to said buckstay.

5. A plastic furnace wall comprising an inner row of water tubes, an outer layer of plastic refractory material, a multiplicity of plates aligned in a row that extends transversely across said water tubes, each of said plates being fastened to its individual tube in a position

5 longitudinal of the axis of said tube and extending outwardly therefrom, each of said plates being provided with a slot extending substantially parallel to and at a predetermined distance from the tubes, an angle iron one leg of which extends into said slots for engagement with said plates thereby aligning and spacing all of the tubes in the row, said tubes, plates and angles being embedded in said plastic refractory layer and forming a unitary wall structure, some of said plates extending outwardly for substantially the same distance from certain of said tubes and further than the remaining plates, a buckstay extending transversely of the tubes adjacent the outer edges of said farther extending plates and having top and bottom flanges substantially parallel to said edges, top and bottom clips provided with slots loosely fitting over the edges of said flanges and welded to said farther extending plates thereby supporting said buckstay from said wall structure and providing freedom for longitudinal expansion of said inner wall structure with respect to said buckstay, and anchoring means for said buckstay comprising certain clips welded to said buckstay from which the buckstay may expand.
